UNITED STATES PATENT OFFICE.

EDWARD S. DAVIS, OF JERSEY CITY, NEW JERSEY, ASSIGNOR TO ROCKWELL FURNACE COMPANY, A CORPORATION OF NEW YORK.

ANNEALING-FURNACE.

1,007,021.

Specification of Letters Patent. Patented Oct. 24, 1911.

Application filed May 4, 1909. Serial No. 493,789.

To all whom it may concern:

Be it known that I, EDWARD S. DAVIS, a citizen of the United States, and resident of Jersey City, in the county of Hudson and 5 State of New Jersey, have invented certain new and useful Improvements in Annealing-Furnaces, of which the following is a specification.

My invention relates to improvements in 10 annealing furnaces and particularly, to furnaces for treating small objects such as balls, cartridges, blanks, and other small parts.

In furnaces for annealing small objects, there is usually employed a conveyer for 15 conveying the objects under treatment from one end of the furnace to the other. This conveyer is usually what is known as a worm or screw conveyer in the shape of a tubular or cylindrical shell having an inter- 20 nal screw-thread, the shell being rotated by any suitable means. There is a tendency of the blanks or objects being treated to become lodged or caught in the conveyer while in transit from one end of the furnace to 25 the other.

The principal object of my invention is to prevent the objects under treatment from becoming caught or stuck in the conveyer.

Other objects of the invention are to im- 30 prove and simplify the construction of the furnace.

In its preferred form my invention com- 35 prises a furnace body in which there is mounted a rotary screw conveyer for con- taining the objects under treatment and for conveying the objects from one end of the furnace to the other. This conveyer may of course be operated by any suitable means, such as worm and gear connections. The 40 furnace is provided with a burner, preferably an oil or gas burner. The furnace body is mounted on a suitable support and for the purpose of preventing the objects from becoming clogged in the conveyer, the 45 furnace is preferably mounted so as to tilt. This mounting of the furnace preferably consists of a hinge joint between the end portion of the furnace and the support. The opposite end of the furnace body is pro- 50 vided with dependent supporting legs or members which serve normally to support the furnace body in a horizontal position. Means are provided for elevating the end of the furnace to impart an inclination to 55 the conveyer and this means preferably con-

sists of a dependent rack on the end of the furnace which is engaged by a pinion, the pinion being operated by any suitable means, such as a hand-wheel and gear connections. When the hand-wheel or other means is operated, one end of the furnace body will be lifted so as to incline the furnace and the conveyer therein at an angle to the horizontal. The objects being fed in at the upper end of the conveyer, they will, of 60 their own weight, assist the feeding operation of the conveyer. By changing the inclination of the conveyer the rate or speed of the feeding operation may be adjusted to suit different conditions. 65

In the accompanying drawings is illustrated the preferred embodiment of the invention but various changes in the construction, combination and arrangement of parts may be made without departing from the 70 scope of the invention.

Figure 1 is a side elevation of my im- 75 proved annealing furnace in its normal horizontal position. Fig. 2 is an end view looking at the feeding end of the furnace. Fig. 80 3 is a longitudinal sectional view of the furnace taken on line 3—3 of Fig. 2, the furnace being tilted to facilitate the feeding operation of the conveyer.

Like reference characters indicate corre- 85 sponding parts throughout the several views.

The support to the furnace is here shown in the shape of a frame 1. The furnace body 2 is of a usual type and is provided in its upper portion with a combustion chamber 90 3 and in its lower part with a heating cham- 95 ber 4 wherein is mounted the conveyer 5. This conveyer preferably consists of and is here shown as a cylindrical hollow casing provided with internal worm or screw- 95 threads 6. The ends of the cylindrical conveyer are of reduced diameter and form journals resting upon rollers 7. The conveyer is preferably rotated by means of a worm 8 engaging a worm gear 9 on one 100 end of the cylinder, the worm being operated by any suitable means, such as a sprocket-wheel 10, sprocket-chain 11 and driving sprocket 12. On account of simplicity and ease of operation, the conveyer is 105 preferably of the worm or screw type illustrated but of course the form of the conveyer may vary, as well as the means for operating the same.

At one end of the furnace, preferably that 110

end which is uppermost when the furnace is tilted, there is provided a feeding hopper 13. The objects to be treated are placed in this hopper which is in communication with the conveyer and the hopper may be carried by the furnace itself or by the extended end of the conveyer. This latter form is illustrated in the drawings and it will be noted that the hopper is affixed to the end of the conveyer, the hopper being frusto-conical in shape and being provided with an internal flange or thread 14 which acts as the conveyer is rotated, to feed the objects into the end of the conveyer. The outward end of the hopper is provided with a retaining flange 15.

In order that the furnace may be tilted to change the inclination of the conveyer, there is preferably provided a hinge joint or joints between one end portion of the furnace and the support. This hinge joint may be of any desired form but preferably one of the hinge members is carried by the furnace body and the other hinge member is carried by the support, the two members being pivoted together by a hinge pin or pintle 17. At the opposite end of the furnace body there are provided dependent legs or supporting members 18 which normally engage the furnace support to hold the furnace in a horizontal position.

The means for adjusting the inclination of the conveyer consist preferably of a dependent rack 19 on the end of the furnace, which is engaged by the pinion 20 which may be operated by any suitable means. These means, however, preferably consist of a hand-wheel 21 on a shaft 22, the shaft having a bevel gear 23 engaging a bevel gear 24 on a worm shaft 25, said worm shaft carrying a worm 26 meshing with a worm gear 27 on the shaft 28, the shaft 28 also carrying the pinion which meshes with the rack. The supporting shaft of the pinion may be conveniently journaled transversely in the support or supporting frame. The rack is curved on an arc having the hinge joint as its center, as the furnace is adapted to swing on this center.

In order that the conveyer may be operated irrespective of the tilted position of the furnace, the driving means must be arranged on the same center as the hinge joint and for this reason the driving gear 12 is preferably journaled directly on the hinge pin 17. This driving gear may in turn be connected with any suitable source of power, as by means of a sprocket 29 and chain 30.

The burner 31, which discharges into the inlet 32 leading to the combustion chamber may be of any desired type. The fuel feeding connections 33 to the burner are provided with a swivel joint 34 in alignment with the center of the hinge joint so that the burner may also be operated irrespective

of the tilted position of the furnace. A pier or baffle may be arranged in front of the burner opening in the usual manner, so as to distribute the fuel evenly throughout the combustion chamber. An arch 36 separates the combustion and heating chambers and this arch is provided with perforations or openings 37 permitting a free circulation of the heating gases between the two chambers. Vents 38 are provided in the top of the combustion chamber and the size of the vents may be regulated by means of the slides 39, which are operated by suitable handles 40.

In operation, the objects to be annealed or treated are placed in the hopper at the upper or feeding end of the conveyer and the conveyer being rotated by suitable power the objects are gradually fed to the opposite end of the conveyer where there is provided an opening 41 in the conveyer in line with the exit opening 42 in the furnace. A discharge chute 43 may form a continuation of the exit opening in the furnace to direct the objects into a cooling tank or other receptacle 44. In this way all the objects are subjected to an even heat and the time or period of the heating may be regulated by adjusting the inclination of the conveyer so as to cause the objects to travel faster or slower.

What is claimed, is:

1. In combination, a supporting frame, a furnace body pivotally connected to the supporting frame, a dependent rack on the opposite end of the furnace body, a pinion journaled in the supporting frame and engaging the said rack, driving connections for operating said pinion, and dependent supporting legs on the furnace body adapted to engage the frame to normally support the furnace in an approximately horizontal position.

2. In combination with a supporting frame and a furnace mounted thereupon, a rotary conveyer in the furnace having an inlet and a discharge end, means for operating the conveyer, pivotal connections between the supporting frame and one end of the furnace, dependent legs on the opposite end of the furnace adapted to normally support the furnace in a horizontal position, a dependent rack on the said opposite end of the furnace, a pinion engaging said rack and journaled in the frame, worm and gear connections for operating said pinion, and a burner for the furnace, tiltable therewith.

3. The combination with a supporting frame, of a furnace, a hinge joint between one end portion of the furnace and the frame, legs on the opposite end portion of the furnace to engage the frame and support the furnace in a horizontal position, a rack dependent from said end portion of the furnace, a transverse shaft journaled in

the frame, a pinion on said shaft engaging the rack aforesaid, a worm gear on said shaft, a worm engaging said worm gear, and means for operating the worm.

5 4. The combination with a support and a furnace body mounted thereon, a hinge joint between the support and furnace body, a burner carried by the furnace, a conveyer within the furnace, driving connections for 10 said conveyer, and fuel feeding connections to the burner, having each a center of movement corresponding to the center of the hinge connection, a rack dependent from the furnace body, a pinion meshing with 15 said rack, and means for operating said pinion.

5 In an annealing furnace, a furnace body provided with a combustion chamber and a heating chamber, an arch separating 20 the two chambers and having openings therein permitting communication between the two chambers, a burner discharging into the combustion chamber, a screw conveyer in the heating chamber, means for changing 25 the inclination of the screw conveyer and means for operating the conveyer irrespective of the position of the same.

6. In combination, a furnace body mounted with a hinge joint so as to be capable of 30 a tilting movement, said furnace having communicating combustion and heating chambers, a burner or burners carried by the furnace and discharging into the combustion chamber, fuel feeding connections 35 to the burner or burners having a movable joint corresponding to the center of the hinge joint, a rotary conveyer within the heating chamber of the furnace, and driving connections for said conveyer also having 40 a center of movement corresponding to the center of the hinge connection.

7. In combination with a tiltable furnace body, a rotary conveyer within the same having smaller journal extensions passing 45 through the end walls of the furnace, bearings on the exterior of the furnace body engaging said journal extensions for rotatably supporting the conveyer, a hopper carried by one end of the conveyer, and driving 50 means engaging the opposite end of the conveyer.

8. A furnace body mounted to tilt and having a perforated arch dividing the furnace into combustion and heating chambers, 55 a burner or burners discharging into the combustion chamber, a rotary conveyer journaled to revolve within the heating chamber, a supply hopper at one end of the conveyer, and the conveyer having a discharge outlet at its opposite end.

9. A furnace body mounted to tilt and having a perforated arch dividing the furnace into an upper combustion chamber and a lower heating chamber, a burner or burners discharging into the combustion chamber,

ber, a rotary conveyer within the heating chamber having a discharge outlet at one end, and a hopper carried by the opposite end of the conveyer.

10. In combination with a support, a furnace body journaled thereon with its end projecting beyond the end of the support and the body having a discharge outlet in said end, means for elevating the opposite end of the furnace body, a rotary conveyer 75 within the furnace body having a discharge opening at one end in line with the discharge outlet, and a rotary hopper carried by the opposite end of the conveyer.

11. In combination, a furnace body 80 mounted so as to tilt and provided with a perforated arch dividing the furnace into communicating combustion and heating chambers, a burner or burners discharging into the combustion chamber, a conveyer 85 located within the heating chamber and provided at one end with an inlet hopper thereto, and a discharge outlet from the opposite end of the conveyer.

12. In combination, a supporting frame, 90 a furnace body pivotally connected to the supporting frame, a conveyer within the furnace body, a dependent rack on the end of the furnace body, a pinion journaled in the supporting frame and engaging the said 95 rack, driving connections for operating said pinion, and dependent supporting legs on the furnace body adapted to engage the frame to normally support the furnace in a substantially horizontal position. 100

13. An annealing furnace comprising a tiltable furnace body, a closed cylinder journaled within the furnace body and provided with a feeding screw on its interior walls, means for rotating said cylinder, a 105 rotary feed hopper carried by one end of the screw conveyer and rotating therewith, the said conveyer having a discharge opening near the opposite end thereof, and the furnace body having a discharge outlet in 110 the bottom thereof in line with the discharge opening in the conveyer.

14. In combination with a furnace body, a rotary conveyer having an enlarged cylindrical portion located within the furnace 115 body, and restricted neck portions extending through the walls of the furnace body, an inlet hopper carried by one of said restricted neck portions of the conveyer, a drive gear on the opposite one of said restricted neck portions, and the enlarged cylindrical portion of the conveyer having a discharge opening therein at a point farthest from the inlet hopper. 120

15. A tiltable furnace body divided into 125 communicating combustion and heating chambers, a burner or burners discharging into the combustion chamber, a conveyer journaled to rotate within the heating chamber, means for imparting rotation to 130

said conveyer, a feed hopper located at one end of the conveyer, said conveyer having an outlet opening near its opposite end, and the heating chamber having a discharge outlet in the bottom thereof in line with the outlet opening in the conveyer.

16. In combination, a support and a furnace body mounted thereon, a conveyer within the furnace body, a pivotal connection between the support and furnace body, means for tilting the furnace body with respect to the support, a burner carried by the furnace, and driving connections for the conveyer and fuel feeding connections for the burner having each a center of movement corresponding to the center of the pivotal connection, whereby the furnace may be operated in any position.

17. In an annealing furnace, a furnace body provided with a combustion chamber and a heating chamber, an arch separating the two chambers having openings therein permitting communication between the two chambers, a burner discharging into the combustion chamber, a conveyer in the heating chamber, means for changing the inclination of the conveyer, and means for operating the conveyer irrespective of the position of the same.

Signed at New York city in the county 30 of New York and State of New York this 2nd day of March A. D. 1909.

EDWARD S. DAVIS.
